UNITED STATES PATENT OFFICE.

SPENCER OTIS, OF CHICAGO, ILLINOIS, ASSIGNOR TO NATIONAL PATENT HOLDING COMPANY, OF SOUTH DAKOTA, OF RAPID CITY, SOUTH DAKOTA, AND CHICAGO, ILLINOIS, A CORPORATION OF SOUTH DAKOTA.

BODY-BOLSTER.

SPECIFICATION forming part of Letters Patent No. 739,916, dated September 29, 1903.

Application filed May 11, 1903. Serial No. 156,651. (No model.)

To all whom it may concern:

Be it known that I, SPENCER OTIS, a citizen of the United States, residing at Chicago, in the county of Cook and State of Illinois, am the inventor of certain new and useful Improvements in Body-Bolsters for Railway-Cars, of which the following is a specification.

My invention relates to that class of bolsters having an upper compression member, 10 a lower tension member removably attached to such compression member, and struts arranged between the compression and tension members provided with means for holding the main sills, subsills, and truss-rods and 15 permitting such sills to be removed without disturbing the upper compression member or truss-rods.

The principal object of the invention is to provide a simple, economical, and efficient 20 body-bolster for railway-cars.

A further object of the invention is to provide a body-bolster for railway-cars having an upper compression member and a lower tension member removably attached thereto, 25 with struts arranged therebetween having pockets adapted to receive and removably hold the car-sills, so as to efficiently hold the sills in the struts and permit their removal by moving the lower tension member without 30 disturbing the upper compression member.

A further object of the invention is to provide a bolster comprising the above elements, in combination with a central bearing-plate extending outward longitudinally of the bolster beneath the sill-supporting struts, whereby such bearing-plate serves to materially 35 strengthen the bolster and support the sills.

A further object is to provide a body-bolster with struts adapted to receive and hold 40 the sills of a car removably therein and a removable lower tension member so arranged in connection therewith as to permit the removal of the sills without disturbing either the upper compression member of the bolster 45 or the sill-bearing struts, such struts also serving to brace the bolster, so as to prevent transverse play.

Other and further objects of the invention will appear from an examination of the drawings and the following description and claims.

The invention consists in the features, combinations, and details of construction herein-after described and claimed.

In the accompanying drawings, Figure 1 is a longitudinal elevation of a body-bolster constructed in accordance with my improvements; Fig. 2, a plan view thereof; Fig. 3, a view in elevation of one of the sill-bearing struts; Fig. 4, a sectional plan view of the strut shown in Fig. 3, taken on line 4; and Fig. 5, a transverse sectional view of the bolster, taken on line 5 of Fig. 1.

In constructing a bolster in accordance with my improvements I provide an upper metallic compression member *a*, having downwardly-extending metallic web portions *b*, attached thereto by means of angle-irons *c* and rivets *d*, such compression member being also provided with curved outer ends *e* and bolts *f* for strengthening the parts and holding them firmly together. A lower metallic tension member *g* is provided and removably attached to such compression member and web portions by means of angle-irons *h*, arranged on both sides of the web. These angle-irons are riveted to such tension member by means of rivets *i* and removably attached to the web by means of bolts *j*, which extend through perforations in the angle-irons of the lower tension member and through the web 75 portions above described, so as to hold the lower tension member removably attached to the upper compression member. Bolts *k* also extend through both the upper compression and lower tension members, at each end thereof, and, together with the bolts and angle-irons already described, serve to still more securely hold the lower tension member removably in position.

A metallic center strut *l* is mounted intermediate the upper and lower 90 members of the bolster and attached to the upper members by means of rivets *m* and to the lower member by bolts *n*, so as to permit the lower member to be removed. This center strut comprises a lower base portion 95 *o* and a pair of side-wall portions *p*, extending upward from such base immediately beneath the center of pockets *q*, which are provided at each side of such center strut for supporting truss-rods *r*, so that the entire 100

weight supported by such truss-rods rests directly over the center of such side-wall portions, the upper ends of which are connected by an integral top wall *s*. The upright side-wall portions, together with the base and top wall of the center strut, are united by a vertical central web and form a hollow strut of one integral piece. On opposite sides of the center strut are mounted side struts *u*, each of which is provided with a base *v*, having downwardly-extending side flanges *w*, adapted to engage the lower tension member of the bolster and hold the parts in position. Each of the side struts is also provided with a standard portion *y*, extending upward from the base and having a pocket 2 at its upper end and immediately over the center thereof adapted to support a truss-rod 3 therein. The inner side of each of such struts is provided with horizontal walls 4 and 5 and a perpendicular wall 6 at right angles thereto, all extending outward transversely of the bolster and forming a pocket adapted to receive and hold in position a sill 7 and efficiently brace the bolster and sills with relation to each other. The lower portion of the inner side of each of these side struts is provided with a perpendicular wall 8, adapted to rest against a sub or draft sill 9, and, together with the center strut and the removable tension member, hold such subsill removably in position between them. The above elements of each side strut are all connected by means of an integral web 10, and the perpendicular wall of the upper pocket portion is provided with perforations 11 for receiving a bolt 12 therethrough, which passes through the sill 7 in such pocket and the main center sill 13 of the car, so as to hold such sills firmly in position and at the same time permit them to be removed upon the removal of the lower tension member without disturbing either the upper tension member or the struts. The struts are all preferably attached to the upper suspension member by means of rivets 14.

The perpendicular wall of the upper pocket portion of each of the struts is of such length, as shown in Fig. 2, as to greatly exceed the width of the upper tension member, and as the inner face thereof rests snugly against the sill, which is mounted in the pocket, it will be readily seen that these struts not only serve to firmly hold the sill in position, but serve as a material strengthening-brace for the bolster, bracing the bolster transversely, longitudinally, and perpendicularly, thus adding greatly to the rigidity of the car.

In order to still further perfect the efficiency and strength of the bolster, a center bearing-plate 15 is provided, comprising a circular base or bearing portion 16, having end portions 17, which extend outward therefrom beneath the sills and to the outer edges of the sill-supporting pockets of the side struts. This bearing-plate is attached to the lower tension member by means of bolts or rivets

18 or in any ordinary and well-known manner, and as it extends entirely beneath the sills and the sill-supporting pocket portions 70 of the side struts it will be seen that it adds materially to the strength of the bolster and serves not only as a bearing-plate, but also in the capacity of a sill-supporting member. Side bearing-plates 19 are attached to the 75 lower tension member, near the opposite ends thereof, by rivets 20 or in any ordinary and well-known manner and are removable with such movable tension member.

The opposite ends of the lower tension member extend downward and toward the center at an incline from the ends of the compression member, and being connected, as above described, to the web portions of the bolster and to the upper member it will be readily 85 seen that the parts are well adapted to stand the great stress and strain to which they are subjected and at the same time provide the lightest possible construction consistent with the strength required. It will also be readily 90 understood by those skilled in the art that the side struts, being provided with pockets at the upper ends thereof which open inwardly, are adapted to efficiently hold the sills of the car therein mounted and form a material 95 brace between such sills and bolster. In this way great rigidity of the parts is as required. The center sills or sub or the draft sills, and particularly the latter, may thus be readily 100 removed and new sills replaced without disturbing the upper tension member of the truss-rods. It will also be seen that although the lower tension member when in position is held rigidly in place, as above described, it is readily removable and serves, in connection 105 with the transversely-extending pocketed struts and elongated bearing-plate, to form a very efficient bolster, well braced in all directions with relation to its respective parts and also with relation to the car-sills. 110

It is desirable that the extreme outer ends of the bolster be made as strong as possible and that the angle of the upper compression member and the inclined portions of the lower tension member be maintained substantially 115 as shown in Fig. 1, so as to afford a high degree of strength and employ as light a construction as possible in connection with the other advantages of a built-up bolster. A pair of filling-plates 22 is therefore mounted 120 at each end of the bolster on opposite sides of the webs and between the transversely-extending flanges of the upper compression and lower tension members, and the ends 23 of the upper compression member are bent inward, so as to engage the extreme ends 24 of the lower tension member, the parts being held in position, as already described, by means of bolts *k* and *f*. By this construction 125 of the outer ends of the bolster it will be seen 130 that the weight, which rests upon the extreme ends of the bolster, may be sustained with the same efficiency substantially as if the lower tension member and its angle-bar extended

directly out to the extreme upper end of the bolster and that the filling-plates substantially reinforce the parts without affecting the removability of the lower tension member.

5 I claim—

1. In a body-bolster, the combination of an upper compression member, a lower tension member removably attached thereto, and 10 strut mechanism mounted intermediate such members and provided with pockets for receiving and removably holding center sills of the car-frame, substantially as described.

2. In a body-bolster, the combination of an 15 upper compression member, a lower tension member removably attached thereto, and strut mechanism attached to the upper compression member and provided with a flanged base in removable engagement with the lower 20 tension member and provided with pockets for receiving and removably holding center sills of a car-frame, substantially as described.

3. In a body-bolster, the combination of an 25 upper compression member provided with web portions extending downward therefrom, a lower tension member removably attached to such upper compression member and web portions, and strut mechanism rigidly attached to the upper compression member and 30 removably attached to the lower tension member and provided with pocket portions for receiving and holding center sills of the car-frame therein, substantially as described.

35 4. In a body-bolster, the combination of an upper compression member provided with web portions extending downwardly therefrom, a lower tension member removably attached thereto, strut mechanism attached to the upper compression member and 40 removably attached to the lower tension member and provided with angular walls extending outwardly transversely of the bolster beyond the edges of the upper compression member 45 thereof, and forming pockets in such strut mechanism for receiving and holding center sills of the car-frame, substantially as described.

5. In a body-bolster, the combination of an 50 upper compression member, a lower tension member, means for removably attaching the lower tension member to the upper compression member, strut mechanism mounted intermediate such members and provided with 55 pockets for receiving and removably holding center sills of a car-frame, and a center bearing-plate attached to the lower side of such bolster and provided with end portions extending outward beneath the said strut mechanism to support the same, substantially as described.

6. In a body-bolster, the combination of an 60 upper compression member, a lower tension member, means for removably attaching the lower tension member to the upper compression member, a center strut mounted intermediate such members provided with up-

right side walls and having pockets immediately over the center of such side walls for supporting the truss-rods of the car, and side 70 struts mounted upon opposite sides of the center strut, each removably attached to the lower tension member and provided with perpendicular and horizontal walls extending outward transversely of the bolster beyond 75 the edges of the upper tension member and forming pockets for receiving the sills of the car, substantially as described.

7. In a body-bolster, the combination of an upper compression member, a lower tension 80 member removably attached thereto, a center strut rigidly attached to the upper compression member and removably attached to the lower tension member and comprising upright side walls having pockets at the upper 85 end thereof for receiving the truss-rods of the car, side struts mounted upon opposite sides of such center strut each rigidly attached to the upper compression member and removably attached to the lower tension mem- 90 ber and comprising an upper standard portion having a pocket for receiving the truss-rod of the car therein, and integral angular walls extending outward transversely of the bolster and forming pockets for receiving and 95 removably holding the sills of the car, and means for removably attaching the lower tension member to the upper compression member and web portions, substantially as described.

8. In a body-bolster, the combination of an upper compression member provided with downwardly-extending web portions, a lower tension member, a center strut rigidly attached to the upper compression member and 100 removably attached to the lower tension member and comprising upright side walls provided with pockets at the upper end thereof for receiving the truss-rods of the car, side struts mounted upon opposite sides of such 105 center strut each rigidly attached to the upper compression member and removably attached to the lower tension member and each comprising an upper standard portion having a pocket for receiving the truss-rod of the car 110 therein and angular walls extending outward transversely of the bolster forming pockets for receiving and removably holding the sills of the car, means for removably attaching the lower tension member to the upper compression member and web portions, and a center 115 bearing-plate attached to the lower compression member removable therewith and provided with end portions extending beneath the pocket portions of the side struts, sub- 120 stantially as described.

9. In a body-bolster, the combination of an upper compression member, a lower tension member removably attached thereto, strut mechanism mounted intermediate such members, a pair of filling-plates mounted at the outer end and between the upper compression and lower tension members, and means for removably holding the lower tension mem- 130

ber in engagement with the upper compression member and filler-plates, substantially as described.

10. In a body-bolster, the combination of an upper compression member provided with transverse flanges, a lower tension member removably attached thereto, strut mechanism mounted intermediate such members, web mechanism attached to the upper compression member and removably connected with the lower tension member, and a pair of filling-plates mounted at each end of the bolster on opposite sides of the web mechanism and in engagement with the transversely-extending flanges of the upper and lower members, substantially as described.

11. In a body-bolster, the combination of an upper compression member, a lower tension

member removably attached thereto, a center strut rigidly attached to the upper compression member and removably attached to the lower tension member, and side struts mounted upon opposite sides of the center strut each comprising an outer upright standard portion provided with a pocket at the upper end thereof for receiving the truss-rods of the car and having perpendicular and horizontal walls extending outward transversely of the bolster beyond the edges of the upper compression member and forming pockets for receiving and removably holding the sills of the car, substantially as described.
